Assistant Examiner — Jennifer L Rempfer

(57) **CLAIM**

The ornamental design for flash lamp epilator, as shown and described.

DESCRIPTION

1. Flash lamp epilator

1.1 is a perspective view showing the flash lamp epilator of our design.

1.2 is a front elevational view thereof;

1.3 is a rear elevational view thereof;

1.4 is a right side elevational view thereof;

1.5 is a left side elevational view thereof;

1.6 is a top plan view thereof; and

1.7 is a bottom plan view thereof.

The portions of the flash lamp epilator shown in broken lines are included for the purpose of illustrating unclaimed portions of the flash lamp epilator and form no part of the claimed design.

1 Claim, 5 Drawing Sheets
